UNITED STATES PATENT OFFICE

HUGO HELLER, OF CEDAR GROVE, WISCONSIN

DESIGN FOR A STOVE

Application filed December 30, 1927. Serial No. 24,697. Term of patent 14 years.

To all whom it may concern:

Be it known that I, HUGO HELLER, citizen of the United States of America, residing at Cedar Grove, in the county of Sheboygan and State of Wisconsin, have invented a new, original, and ornamental Design for Stoves, of which the following is a specification, reference being had to the accompanying drawing, forming a part thereof.

The drawing is a front perspective elevation of the stove showing my new design.

I claim:

The ornamental design for a stove as shown.

HUGO HELLER.
